UNITED STATES PATENT OFFICE.

FRANK A. WASSON, OF MILWAUKEE, WISCONSIN, ASSIGNOR TO BADGER MANUFACTURING CORPORATION, OF MILWAUKEE, WISCONSIN, A CORPORATION OF DELAWARE.

BUMPER-BAR.

1,317,112.

Specification of Letters Patent. Patented Sept. 23, 1919.

Application filed March 25, 1919. Serial No. 285,082.

To all whom it may concern:

Be it known that I, FRANK A. WASSON, a citizen of the United States, and resident of Milwaukee, Milwaukee county, Wisconsin, have invented new and useful Improvements in Bumper-Bars, of which the following is a description, reference being had to the accompanying drawings, which are a part of this specification.

10 This invention has for its object to provide a bumper bar for automobiles with an end closure that is integral and hence incapable of being lost.

Heretofore the tubular bumper bars have either been left open at their ends, which gives them an unfinished appearance, or they have been provided with wooden plugs driven into them to receive a wood screw for holding an ornamental cap in place. The 20 wooden plug in the end of the bumper bar forms an insecure anchoring means for the cap as it is liable to shrink and become loose so that the caps with the plugs are frequently lost, and the dealers are constantly 25 called upon for renewals. The high polish or ornamental finish that is usually given to the bumper bars makes it undesirable to secure the cap in place by screws or pins or other means requiring machine work on the 30 end of the bar.

It is the object of this invention to provide a closure for the end of the bumper bar which will have the same neat and ornamental appearance as the remainder of the 35 bar, and being integral with the bar will be incapable of being lost.

With the above and other objects in view the invention consists in the bumper bar as herein claimed and all equivalents.

40 Referring to the accompanying drawings in which like characters of reference indicate the same parts in different views:

Figure 1 is a perspective view showing a portion of the bumper bar with the end constructed in accordance with this invention;

45 Fig. 2 is a similar view thereof with the ears forming the end closure only partly bent;

Fig. 3 is a view of the blank from which 50 the bar is formed; and,

Fig. 4 is a view showing the manner in which the ears contact with each other along their outer edges to form a close joint.

55 In these drawings 10 indicates a tubular bumper bar which is formed as usual from

a blank 11 bent along fold lines 12 to the tubular form which may be square or of other angular shape in cross section. The meeting edges of the tubular bar are usually electrically welded. The ends of the blank 60 11 are serrated to provide triangular ears 13 uniting along the dotted fold line 14 with the respective faces of the tubular bar between the dotted fold lines 12. The shape of these triangular ears 13 is such that when 65 the blank is folded to its tubular form and the ears are bent over along their fold lines 14, each ear will contact with the edge of the next ear before reaching the plane of the fold lines, thus producing a pyramidal closure 70 at the end of the bumper bar formed by the ears integral with the faces thereof. The shearing action of the dies by which the sheet metal blank is cut leaves the edge slightly oblique, and in folding up the blank 75 11 the acute angles of the oblique edges are placed outermost, which insures a close fitting contact of the edges of the bent over ears as indicated in Fig. 4, the oblique edges of the ears enabling them to contact only 80 along their outer surfaces. It is as if these bent over ears were mitered to produce their close fit, though the oblique edges are incidental to the operation of the cutting dies.

In practice it is preferred to fold the ears 85 to a partly closed position, such as shown in Fig. 2 and then subject them to pressure from dies of the shape of the finished bumper bar. The pyramidal end of the bumper bar is nickel-plated and burnished 90 or otherwise finished in the same manner as the remainder of the bar so that it presents the same ornamental appearance. In order that the bumper bar may not have a tendency to float in the electroplating bath, provision is made for the admission of the 95 liquid to the interior thereof. For this purpose the end of each of the triangular ears is blunted at 15 so that when they are folded together these blunted ends form a small 100 opening at the center of the closure through which air and liquid may pass.

What I claim as new and desire to secure by Letters Patent is:

1. A bumper bar having triangular ears 105 at its ends bent to engage each other along their side edges to close the end of the bar.

2. A tubular bumper bar angular in cross section provided with triangular ears at the ends of its respective faces, said ears being 110

bent along lines in a common plane and contacting with each other to close the end of the bumper bar.

3. A tubular bumper bar of angular cross section having triangular ears at the ends of their respective faces, said ears being folded along lines in a common plane transverse of the bar and contacting with each other along their side edges and having their ends blunt to leave a central opening in the closure for the end of the bar.

4. A tubular bumper bar formed of a die cut sheet metal blank provided with serrated ends, said blank being folded into tubular form with triangular ears formed by the serrations at the ends of the faces of the bar, the oblique die cut edges of the blank being so arranged that the acute angles thereof are outermost so that the ears fit together as if mitered.

5. A bumper bar having triangular ears at its ends bent to engage each other along their side edges to close the end of the bar, one or more of the ears being cut away to provide an opening in the closure.

6. A bumper bar having ears at its ends bent to place their side edges in juxtaposition to substantially close the end of the bar.

7. A tubular bumper bar having integral ears at its ends, said ears being bent along lines in a common plane to form closures for the ends of the bar.

In testimony whereof I affix my signature in presence of two witnesses.

FRANK A. WASSON.
